United States Patent Office

Des. 225,092

Patented Nov. 7, 1972

225,092

TIRE

Iain C. Mills, Sutton, England, assignor to Dunlop Holdings Limited, St. James, London, England

Continuation-in-part of design applications Ser. No. 22,172 and Ser. No. 22,173, both Apr. 1, 1970.
This application Jan. 13, 1971, Ser. No. 106,320

Claims priority, application Great Britain Oct. 9, 1969;
Oct. 17, 1969

Term of patent 7 years

Int. Cl. D12—15

U.S. Cl. D90—20

FIG. I.

FIG.2.

FIG.3.

FIG. 4.

FIG. 5.

FIG. 6.

FIG. 1 is a perspective view of the tire of my new design;

FIG. 2 is a fragmentary perspective view;

FIG. 3 is a fragmentary plan view;

FIG. 4 is a perspective view of a second embodiment;

FIG. 5 is a fragmentary perspective view of the second embodiment; and

FIG. 6 is a fragmentary plan view of the second embodiment.

The tread designs shown are repeated throughout the circumference of the tires and the sides opposite to those shown are mirror images thereof.

This application is a continuation-in-part of applications Ser. Nos. D. 22,172 and D. 22,173 both filed Apr. 1, 1970 and both now abandoned.

I claim:

The ornamental design for a tire, as shown and described.
